ABSTRACT OF THE DISCLOSURE

A ball valve having alternatively functioning inlet and outlet passages of different standard diameters and therefore selectively connectible to the underside outlet of a sink drain in accordance with and depending upon the diameter dimension of the drain outlet. The valve is comprised of two body sections, one of the latter having an hexagonal peripheral portion integral therewith to facilitate and enable achievement of positive securement of either end passage to the sink drain. A control rod is provided to enable movement of the ball to the fluid-flow or fluid-restricting positions, said control rod being extended to at least the vertical front wall of the sink.

This invention relates generally to sink drain control means and more particularly to a ball-type drain valve adapted for connection to either of two standard drain diameters and being controllable from a position beneath the sink and proximate with respect to the vertical front wall thereof.

Drain valves heretofore utilized in controlling the discharge of sink waste were of the liftable gate-type wherein the gate is raised to permit the discharge of fluid.

Heretofore, the discharge of sink waste has generally been accomplished from within the sink, manipulation of a valve gate seated directly over the drain pipe being required. Thus, the sink user's hand had to be immersed in the waste fluid for such manipulation, notwithstanding the attendant lack of sanitation and unpleasantness caused thereby.

The utilization of undersink waste-discharge-control devices has, in the past, been infrequent, essentially because of inconvenience of operation, clogging and cleaning difficulties. Such drain valve devices, being of the lifting and seating gate construction, depend in part upon gravity for their operation and consequently require a specific vertical inlet and outlet orientation. Thus, a particular valve of this character could be adapted directly to a sink drain outlet of one of the two most commonly prevalent sizes, another valve being required for the other prevalent size drain outlet. To enable accommodation of such drain valves to more than a single sink drain outlet size, reduction or expansion fittings are required, thereby greatly adding to the expense of installing these devices.

Further, gate-valved sink drains are relatively slow with respect to their discharge rates and accordingly require complex means for lifting or unseating the gate to a degree permitting increased and therefore useful flow rates.

Consonant with the foregoing, the instant invention has for an object the provision of a novel apparatus for facilitating the controlled discharge of fluid wastes from a sink.

2

Another object of the present invention is to provide an apparatus which will permit rapid draining of a sink and which is controllable from the underside of the sink.

A further object of the present invention is the provision of an improved drain valve, the flow rate of which can be readily regulated and which can accommodate the flow of relatively larger solids than can be accommodated in prior art sink-drain devices.

A still further object of the instant invention is the provision of a new and useful undersink drain valve having extended control rod means and which can be installed with either of its terminal flow passages functioning as the inlet or outlet passage.

Still another object of the present invention is to provide simplified means for adapting a drain valve to either of two standard sink drain fittings.

A further object of this invention is to provide a drain valve comprised of two body sections, each section having a seat portion integral therewith, said two seat portions cooperating to provide positive seating for ball means revolvable thereon.

A still further object of the instant invention resides in the provision of a novel drain valve which is relatively simple of construction, e.g., requiring no gaskets, which is strong, durable and unlikely to become jammed or clogged thereby substantially minimizing maintenance problems.

Other objects and advantages of the invention will become apparent upon reading the following description taken in conjunction with the accompanying drawings in which:

FIGURE 1 is a perspective view of a typical sink to which the present drain valve is applicable, the control rod means of said valve being visibly shown extending proximately of the vertical front wall of the sink basin;

FIGURE 2 is an enlarged, exploded, perspective view of the body sections of the valve and the ball means thereof;

FIGURE 3 is a side elevational cross-sectional view of the valve directly connected to the underside of the sink drain;

FIGURE 4 is a side elevational cross-sectional view of the valve directly connected, in an inverted manner, to the underside of the sink drain.

FIGURE 5 is a view of the invention including an extension fitting between the valve inlet passage and the sink drain, and illustrating the ball means in closed position; and

FIGURE 6 is a view of the valve connected to the sink drain in inverted position, an extension fitting being disposed between the valve inlet passage and the sink drain, and the ball means in closed position.

It will be understood that the foregoing general objectives and the following detailed description as well, are exemplary and explanatory but are not restrictive of the invention.

Referring now in detail to the present preferred embodiment of the invention illustrated in the accompanying drawings, the drain valve, designated generally by numeral 1, comprises first and second body sections, said sections being also designated generally by numerals 2 and 4, respectively. Said first section, it will be observed, includes a head portion 6 which has an internally threaded first passage 8 and an externally threaded stem portion 10, said stem portion extending axially and integrally of said head portion and terminating with free end 11,

the latter being inwardly and arcuately bevelled to function as the first annular seat to be described hereinbelow.

As will be seen second body section 4 includes conduit portion 12, the periphery thereof or internal wall 14 of said second body section being threaded as shown, the threaded portion 14 extending to end 16 thereof. Disposed at and extending inwardly of the other end 18 of said second body section is internally threaded second passage 20, a second annular seat 22, to be further discussed hereinbelow, being located at the juncture of said conduit portion 12 and said second passage 20.

With reference to FIGURES 3-6 of the drawings wherein the assembled drain valve unit 1 is illustrated, said stem and conduit portions 10 and 12, respectively, are threadedly connected at 24 whereby said conduit portion extends longitudinally through said valve in communication with first and second passages 8 and 20, said latter passages being located at the respective ends of said valve.

Said aforementioned first and second annular seats 11 and 22, respectively, are as shown, provided integrally of said respective body sections, said seats being relatively spaced and concentrically disposed with respect to the longitudinal axis X-X of said valve.

Ball means 26, having a spherically-shaped external surface 26 and a slot 28 within said surface, is revolvably seated contiguously between said respective seats, said ball means having a passage 30 therethrough.

Control rod 32, which extends through aperture 34 disposed through the side wall of said second body section and into the conduit portion thereof, includes a key 36 at one extremity thereof, said key being removably received within said slot. Accordingly, upon rotation of said control valve by manipulation of handle 38 thereof, said ball means can be moved between the opened position shown in FIGURES 3 and 4 and the closed position shown in FIGURES 5 and 6 of the drawings. Thus, as will be observed, when said ball means occupies the opened position, fluid will be allowed to flow through said conduit portion 12; while when in the closed position, fluid flow through said conduit portion will be precluded. Further, intermediate positions of said ball means can be utilized to control fluid flow over a relatively wide range.

Accordingly, by dint of the threadedly united two-section valve construction as described, said sections can be tightened against the ball means as required, said first and second annular seats being tightly securable with respect to said ball means to effectuate positive seating thereof.

Also as shown, said first and second threaded passages 8 and 20 are of different diameter, the former passage being illustrated as being larger than the latter. Accordingly, in view of the ball means construction herein afforded, the present drain valve can be installed whereby said passages can alternately serve as the inlet or outlet passage, the installation position being selected in accordance with the corresponding size of the drain outlet 40. Inasmuch as such drain outlets are commonly provided in one of two standard sizes, the drain valve can readily be adapted directly to either of said sizes, FIGURES 3 and 4 being illustrative of such respective installations. Further, extension pipe means 42 as shown in FIGURES 5 and 6 may be utilized where the drain valve is to be advantageously positioned at lower elevations with respect to the bottom wall 44 of the sink.

Of further import, the head portion 6 of the present drain valve is of hexagonal configuration as shown in FIGURE 2 of the drawings, installation and removal of said valve with respect to the sink drain and assembly and disassembly of the valve itself being greatly facilitated by the wrench-gripping surface thereby provided.

In view of the extended nature of the control rod 32, the latter being at least twelve inches in length and preferably extending at least to the front vertical wall 46 of the sink, a support sleeve 48 is provided normally and in-

tegrally of said second body section 4, said sleeve being externally threaded and having a passage 50 therethrough in axial alignment with aperture 34 of said second body section, said passage and aperture being of equal diameters and said control rod being rotatably received within said sleeve passage. Connecting collar 52, disposed annularly about said control rod, includes an internally threaded portion 54 which is connected to said support sleeve to thereby retain said ball and control rod in connected relation. Thus, by dint of said sleeve 52, control rod 32 is rigidly supported notwithstanding the moment-arm created by the exceptional length thereof.

What is claimed is:

1. A valve adapted for connection to the underside outlet of a sink drain, said valve comprising first and second body sections, said first section including a head portion having an internally threaded first passage and an externally threaded stem portion, said stem portion extending axially and integrally of said head portion, and terminating in a free end, said second section having an at least partially internally threaded conduit portion extending to one end thereof and an internally threaded second passage at the other end thereof, a support sleeve extending normally and integrally of said second body section, said sleeve being externally threaded and having a passage therethrough in axial alignment with an aperture in said second body section, said passage and aperture being of equal diameters, said stem and conduit portions being threadedly connected whereby said conduit portion extends longitudinally through said valve in communication with said first and second passages, said passages being at respective ends of said valve and being of relatively different diameters, first and second annular seats provided integrally of said respective first and second body sections, said seats being relatively spaced and concentrically disposed with respect to the longitudinal axis of said valve, ball means revolvably seated contiguously between said respective seats, said ball means having a passage therethrough and being revolvable between an opened position allowing fluid to flow through said conduit portion and a closed position precluding said flow, control rod means, one end thereof extending through said aperture in said second body section and into the conduit portion thereof said control rod means being rotatably received within said sleeve passage, said control rod means being removably connected to said ball means permits movement of said ball means between said opened and closed positions.

2. A valve as set forth in claim 1 wherein the exterior of said head portion is of polygonal configuration.

3. A valve as set forth in claim 1 wherein said first annular seat is located at the free end of said stem portion, and said second annular seat is located at the juncture of said conduit portion and said second passage.

4. A valve as set forth in claim 1 wherein said one end of said control rod means comprises a key, said ball means having a spherically-shaped external surface and a slot within said surface, said key being removably receivable within said slot, and the other end of said control rod means having a handle connected perpendicularly thereto.

5. A valve as set forth in claim 4 wherein said handle means extends at least twelve inches from said second body section.

6. A valve as set forth in claim 1 including extension pipe means threadedly connected to said first passage.

7. A valve as set forth in claim 1 including extension pipe means threadedly connected to said second passage.

8. A valve as set forth in claim 1 wherein the exterior of said head portion is of hexagonal configuration and wherein the diameter of said first passage is larger than the diameter of said second passage.

9. A valve as set forth in claim 1 including a connecting collar disposed annularly about said control rod means, said collar having an internally threaded portion and being threadedly connected to said support sleeve to

thereby retain said ball and control rod means in connected relation.
